(57) **CLAIM**

The ornamental design for an eyeglass temple with a bluetooth headset, as shown and described.

DESCRIPTION

FIG. 1 is a front perspective view of an eyeglass temple with a bluetooth headset showing my design;
 FIG. 2 is a rear perspective view thereof;
 FIG. 3 is a front elevational view thereof;
 FIG. 4 is a rear elevational view thereof;
 FIG. 5 is a left elevational view thereof;
 FIG. 6 is a right elevational view thereof;
 FIG. 7 is a top plan view thereof;
 FIG. 8 is a bottom plan view thereof; and,
 FIG. 9 is a perspective view of the eyeglass temple in accordance with my design, shown in its environment thereof.
 The broken lines shown in FIG. 9 show environment for illustrative purposes only and form no part of the claimed design.

1 Claim, 7 Drawing Sheets
